METHOD OF ESTABLISHING A FLUID-TIGHT CLOSURE

William H. Bowes, Peterborough, Ontario, Canada, assignor to Atomic Energy of Canada Limited, Ottawa, Ontario, Canada

Filed May 6, 1958, Ser. No. 733,446

Claims priority, application Canada March 25, 1958

1 Claim. (Cl. 29—446)

This invention relates to a method of establishing a fluid-tight closure, and has for its object the provision of a closure for a tubular member. The term "tubular member" is chosen for convenience of description but is not intended to imply that the invention is restricted to use with a member of circular cross-section, the invention being applicable to any annularly shaped member whatever its shape in cross-section. Similarly it is not the intention that "tubular member" should imply an elongated tubular vessel; the tubular member may be short, and may comprise merely a protuberance on a vessel of any shape.

For the purpose of the invention, there is provided a closure assembly for the tubular member, such assembly comprising an annular seating surface formed on the tubular member, a flexible sealing disc mounted with a sealing area of the inner face thereof in register with such annular seating surface for pressure sealing engagement therewith, a plug for engagement with the tubular member, bearing surfaces projecting from the inner end of the plug positioned for engagement with areas of the outer face of the disc radially intermediate the centre thereof and said sealing area, and disc-controlling means for deflecting inwardly the centre of the disc to force the sealing area thereof against said seating surface, such means extending from the exterior of the assembly to the central area of the disc whereby to be operable from the exterior of the assembly.

The method according to the invention consists of initially partially assembling the parts by introducing the plug into the tubular member sufficiently to bring the sealing area of the disc at least approximately into substantially pressureless contact with the seating surface, acting on the disc-controlling means to force the centre of the disc inwardly and urge its sealing area into pressure engagement with the seating surface, then moving the plug further into the tubular member to bring its bearing surfaces into pressure engagement with said intermediate areas of the disc, and finally releasing the disc-controlling means.

The manner of carrying the invention into practice is illustrated, by way of example, by the structures shown in the accompanying drawings, in which:

Figure 1 is a central section showing a closure assembly in partially closed condition;

Figure 2 is a view similar to Figure 1 showing the parts at a later stage in carrying out the closing operation;

Figure 3 is a further similar view at a still later stage in this operation;

Figure 4 is another view of the same parts with the assembly in the fully closed position; and

Figure 5 is a view of an alternative construction, showing the parts in a position corresponding to that of Figure 1 of the first construction.

Referring firstly to Figure 1, this view shows a tubular member 10 an open end of which is to be provided with a fluid-tight closure. For this purpose, the member 10 is provided with an internal thread 11 constructed for

2

engagement with external threads 12 formed on a plug 13 adapted to engage and form the main physical structure, but not the fluid-tight aspect, of the closure.

Alternatively, instead of providing a threaded engagement between the plug and the tubular member, the plug could slide into the tubular member and be held therein by suitable means such as a transversely extending wedge passing through the tubular member and through a transverse passageway in the plug. This method of retaining the plug is especially suitable when the cross-section of tubular member and plug is non-circular (say elliptical) and the plug thus cannot be rotated in the tubular member.

At its inner end, the plug 13 is formed with an annular projection 14 which provides bearing surfaces acting against the rear of a flexible circular disc 15 which is supported within an annular flange 16 projecting from the inner end of the plug 13. It is not essential that a single annular projection 14 be employed. A series of 20 annularly disposed discrete projections could be employed, instead, to provide the necessary "bearing surfaces." A circular gasket 17 extends across the inner face of the flexible disc 15 and around the annular flange 16 into an annular cavity 18 formed between the tubular member 10 and the plug 13. The tubular member 10 is formed with an annular seating surface 19 positioned for engagement by the outer peripheral sealing area 26 of the disc 15 (with the sealing gasket 17 interposed). The surface 19 is preferably of circular form, but can 30 follow any other annular shape that may be adopted for the tubular member.

A turning bar 24 is formed on the outer end of the plug 13 for rotating the same.

Within a central hole 20 extending through the plug 35 13 and turning bar 24 there is slidably mounted a push rod 21 which terminates at its inner end in a bearing surface 22 and at its outer end in an operating surface 23.

Figure 1 shows the parts assembled but with the assembly brought only to the partially closed position, i.e. with the sealing area 26 of the disc 15 approximately in 40 gently, i.e. substantially pressureless contact (through gasket 17) with the seating surface 19.

To move the parts to the fully closed position, a predetermined axial force is firstly applied from the exterior to the push rod 21, thereby forcing inwardly the centre of the flexible disc 15 and arching the same in a manner shown in Figure 2 and establishing pressure contact between sealing area 26 and seating surface 19. With the 50 push rod 21 and hence the disc 15 held in this position the plug 13 is rotated by the bar 24 to bring the bearing projection 14 firmly up against the rear of the disc 15, the projection 14 bearing against an annular area 27 of the disc 15 that is radially intermediate the centre of the disc and the sealing area 26. This is the position shown in Figure 3. By operating in this manner there is no relative rotation between the sealing area 26 of the disc 15 and the seating surface 19, which parts form the fluid-tight seal, or between these parts and the interposed gasket 17, during a time when the parts are in 55 pressure contact with one another.

Finally, the push rod 21 is released, as shown in Figure 4, to allow the disc 15 to move back. The remaining deflection in such disc is shown in somewhat exaggerated form in Figure 4 for clarity of illustration. In fact, all the drawings exaggerate the deflections from those normally experienced in practice, otherwise clear illustration would not result.

When the parts take up this final position, the disc 70 15 is still stressed, with the result that it exerts a substantial sealing pressure through its sealing area 26 on the seating surface 19, the projection 14 acting as a ful-

crum. Fluid pressure can then be introduced into the interior of the member 10, and such internal pressure will tend to increase the sealing pressure between the area 26 and the seating surface 19, the annular projection 14 continuing to act as a fulcrum for this action.

Demounting of the assembly is carried out by a simple reversal of the closing steps described above.

In the alternative construction shown in Figure 5, the push rod 21 is rigidly connected to the flexible disc 15 and serves to support it. In this case an annular gasket 25 is used to replace the circular gasket 17. In other respects the structure and manner of operation of this device is similar to that of the embodiment already described.

I claim:

A method of establishing a fluid-tight closure in an assembly comprising a tubular member, an annular seating surface formed on said member, a flexible sealing disc mounted with a sealing area of the inner face thereof in register with said annular seating surface for pressure sealing engagement therewith, a plug for engagement with said tubular member, bearing surfaces projecting from the inner end of said plug positioned for engagement with areas of the outer face of said disc radially intermediate the centre thereof and said sealing 25

area, and disc-controlling means for deflecting inwardly the centre of said disc to force the sealing area thereof against said seating surface, said means extending from the exterior of the assembly to the central area of said disc whereby to be operable from the exterior of the assembly; said method comprising initially partially assembling the parts by introducing the plug into the tubular member sufficiently to bring said sealing area of the disc at least approximately into substantially pressureless contact with said seating surface, acting on said disc-controlling means to flex the centre of the disc inwardly and urge its sealing area into engagement with said seating surface to increase the pressure between said sealing area and said seating surface, then moving said plug further into said tubular member to bring said bearing surfaces on said plug into pressure engagement with said intermediate areas of said disc, and finally releasing said disc-controlling means.
